UNITED STATES PATENT OFFICE.

JUAN G. HOLGUIN BURBOA, OF HERMOSILLO, MEXICO.

PLATEN MECHANISM.

1,098,556.

Specification of Letters Patent.

Patented June 2, 1914.

Original application filed February 13, 1913, Serial No. 748,219. Divided and this application filed August 20, 1913. Serial No. 785,762.

To all whom it may concern:

Be it known that I, JUAN G. HOLGUIN BURBOA, a citizen of the Republic of Mexico, residing at Hermosillo, in the county of Hermosillo and State of Sonora, Mexico, have invented a new and useful Platen Mechanism, of which the following is a specification.

The present invention relates to improvements in typewriting machines, and more particularly to the mechanism for imparting rotary movement to the platen for letter spacing and longitudinal movement for line spacing, the present application being a divisional application of my copending application filed February 13, 1913, Serial No. 748,219, one object of the invention, being the provision of means whereby a vertically movable platen has imparted vertical movement thereto for line spacing and rotary movement thereto for letter spacing, the platen being held in a vertical position at all times.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a diagrammatic perspective and sectional view taken from the rear of a typewriting machine showing the main motor and the control mechanism for rotating and vertically moving the platen. Fig. 2 is a cross sectional view through the main casing of a typewriting machine at a point below the type basket showing the position of the various selectors, the operating motors and the platen. Fig. 3 is a central vertical cross sectional view through the casing with a greater portion of the type basket removed, the platen and carriage being shown in elevation. Fig. 4 is a diagrammatic plan view of the various mechanisms for controlling the rotation of the platen and adjacent mechanisms of the typewriting machine. Fig. 5 is an enlarged detailed end elevation of the platen, showing the mechanism for imparting intermittent rotary movement for letter spacing. Figs. 6 and 7 are enlarged detail views of

a portion of the letter spacing mechanism. Figs. 8, 9, 10, 11, 12 and 13 are detail views illustrating the construction and arrangement of the motors and motor controls, for imparting vertical line spacing movement to the platen.

Referring to the drawings, the numeral 1 designates the frame of a typewriting machine, which has mounted therein a plurality of selectors 2, by means of which the vacuum effect is transmitted to the desired mechanism of the typewriting machine, the keys 3 controlling the selectors or any combination thereof so that the air displaced by the motors 4 through the vacuum chamber 5, will properly effect the desired mechanism, and as particularly set forth in the above mentioned application.

The platen 13 is disposed for vertical movement instead of the usual horizontal movement for producing writing from the top to the bottom of the page, while the same is rotated horizontally during the writing of a line, the same being actuated a space or a number of spaces at a time according to the number of type that are presented to the platen through the actuation of the keys and combinations thereof.

A lower cross-bar 57 is connected by means of the two vertical rods 58 to the upper cross-bar 59, each of the rods 58 being movable and journaled for vertical sliding movement within the stationary or fixed tubes 60 mounted properly within the casing. The axle 61 of the platen 13 is journaled in the cross-bars 57 and 59 for rotation while the bars or rods 58 are mounted within the tubes 60 for vertical movement. The said rods 58 and cross-bars 57 and 59 constitute the carriage for the platen and are bodily movable vertically. As shown in Fig. 1, the incased spring 56, is connected to the frame and cross bar 57 to elevate the carriage, this structure being identical with the adjustable spring devices now used.

In order to produce the necessary horizontal rotation of the platen 13 to present a new space for the presentation of a type thereto, after the actuation of the type bar controlling keys of the machine, the motors 62 and 63, which are of the suction bellows type, are provided, and have their control through the vacuum chamber 5 and the selector 2, one of the levers 42 being the control therefor, so that these motors 62-63 will be op-

erated to operate the crank shaft 64 which is journaled in the respective bearings 65 and 66. As clearly shown in Fig. 1, there is keyed upon the crank shaft 64, a gear 67, which under normal conditions is in mesh with the gear 68 carried upon the lower end of the oscillatory and rotatable shaft 69, this shaft 69 being journaled within the swivled or swinging block 70 disposed between the spaced arms 71 of the supporting lugs 72. The supporting lugs 72 are secured to one of the tubular supports 60 which constitutes one of the carriage guides. The shaft 69 being thus rotated, rotates the upper gear 73, which is at that time in mesh with the gear 74 upon the lower end of the vertical shaft 75, this vertical shaft 75 having keyed upon it, the intermediate gear 76 for actuating the escapement 82, as will presently appear, and the upper gear 77, which constitutes the main operating gear for the rotation of the platen 13, the dial 202, and the marginal control 206.

A gear 78 is in mesh at all times with the gear 77 and transmits motion through the large gear 79 to the long vertical gear 80 which is disposed vertically of the machine and in mesh at all times with the gear 81, connected to the platen 13 and its shaft 61 so that regardless of the position of the platen relatively to the casing in its vertical up and down movement, the gear 81 will cause the desired rotation of the platen to present a new space for the presentation thereto of the type. By reason of the fact that the lever 42 with the selector 2 for actuating the motors 62 and 63, are operated at all times through one of the levers 40 controlled by any one of the keys 3, the platen 13 will be rotated one space for each type, but should four type be presented, the motors 62 and 63 will be actuated to impart to the platen 13 a movement equal to five spaces which constitute the four spaces for each type and the extra space between the type for the next space to be printed.

In order to provide a means for indicating at a glance the position of the platen relatively to the type line being printed, a gear 200 is in mesh at all times with the gear 201 which actuates the dial 202 disposed at the forward upper edge of the machine and in ready view of the operator.

The control device for the respective motors 62 and 63 is clearly shown in Figs. 8 through 13, and includes the two stationary plates 301 and 302 which have mounted for oscillation therebetween, the controlling rotatory disk 303, the tubes being led from the vacuum chamber 5 to the ports of the disk 301 and to the motors 62 and 63 through the respective tubes 62' and 62'' and 63' and 63'' to the disk 302, the rotatory disk 303 being provided with the recessed portion, as clearly shown in Fig. 12, so as to cause the

interlinking or intercommunication between the respective tubes 62' or 62'' or 63' or 63'' to impart the necessary action to the movable bellows of the motors 62 and 63, respectively, and consequently cause the desired actuation of the shaft 64.

In order to operate the platen carriage to impart to it the necessary upward vertical movement, due to the line spacing and also to impart to it the descending vertical movement during the change from a written page to a new page, the shaft 69 must be swung so as to disengage the gear 73 from the gear 74 and the gear 68 from the gear 67, this being affected through the motor 83, controlled through the selector 2, said motor 83 being operably connected to the bell crank lever 84 which is connected to the sliding block 85 mounted upon the two spaced pins 86 of the support 72. This block 85 has the shaft 69 journaled therethrough and when moved by the motor 83, causes the positioning of the gear 87 into mesh with the gear 88, so that the shaft 69 is rotated to actuate the gear 89, and as the bevel gear 89 is placed in mesh with the bevel gear 90, the shaft 91 journaled in the bearings 92 and carrying the gear or pinion 93 is rotated. This rotation controls the motion to the toothed rack 94 of the platen carriage, said rack being disposed between the cross-bars 57 and 59, and causes the platen carriage to be elevated the desired spaces, as for instance, one line, two lines or three lines, or will cause movement downwardly of the platen 13 from its highest to its lowest point upon the presentation of a new page.

The escapement mechanism for permitting the movement of the carriage and platen due to the shifting from one line to the next and for varying spaces as for instance one, two and three spaces, consists of the toothed rack 95 carried at the opposite side of the platen to the rack 94, the same having in mesh therewith at all times, the gear 96 carried upon the swinging shaft 96', the block 97 being constructed and arranged according to the sliding block 97 for swinging the shaft and placing the gear 96 into and out of engagement with the rack 95 according to the actuation of the motor 99 and consequently the desired spacing required. The block 100 is the swingingly journaled block for the shaft 96', while the escapement 101, shown at the right in Fig. 1 and which is constructed similarly to the escapement 82, is provided for actuating the shaft 96', or rather controlling the actuation thereof, to permit the movement of the platen and carriage the desired and selected spacing distance from one line to the next.

In order to permit the upward and downward movement of the carriage, the adjustable marginal stop 102 with the pneumatic buffer 103 is provided to be engaged by the

cross-bar 59 when the carriage is returned from its extreme upper to its lowermost position upon the presentation of a new page, while the adjustable marginal stop 104 and its projecting end 105 is provided to engage the lower cross-bar 57 of the carriage and thus limit the upward movement of the same. These two stops are adjustably mounted upon the guide rod 106 which is fixed to the frame of the machine so as to provide a rigid support therefor.

In order that the platen, as before described, may be rotated a single space or up to five spaces in the present instance, an escapement device, as clearly illustrated in Figs. 5, 6 and 7 is provided, this escapement device also being similar to the device 101 for controlling the vertical movement of the platen carriage, both of such devices being constructed for control from the key board and through the vacuum chamber 5. The gear 76 in this instance as before stated, is geared to the rotatable casing 82' of the escapement device 82 and this casing is provided with the teeth 107 and the facial pins 108. A fixed frame 109 is provided with the two parallel rods 110 upon which are slidably mounted, the sleeves 111 which bodily carry the pawl carriage 112, the fixed lug 113 being connected to one end of the carriage and having fast thereto, a pin 114, which forms a journal for the points 115 of the respective tooth engaging pawls 116, 117 and 118, there being a single pawl 116 formed integral with the lug 113, a plurality of four intermediate pawls 117 and a single flexible pawl 118. This finger 118 is provided with the flexing end 119, which is normally held aligned with the main body of the finger 118 by means of the spring 120. Each of the respective pawls 118 and 117 are provided with a pin 121, which overlaps the adjacent pawl, as clearly shown in Fig. 6, so that the fixed pawl 117 limits the movement of the respective pawls in the direction of the arrow Fig. 5 and consequently in a position for engaging the teeth 107 to lock the disk 82 against rotation. The springs 119' are connected to the lug 118' of the various movable pawls 117 and 118 to form a resilient means for permitting the back stepping or back spacing of the disk 82 and consequently the platen 13 by means of the back spacing motor 129 which is provided with the flexing pawl 130 connected by the pivoting lug 131 to the movable section 132 of the motor. This operation is controlled from the key board to back space the disk 82 one space as desired, and as illustrated in dotted lines Fig. 5.

In order to control the actuation of the carriage 112, the same being manipulated in its normal position by means of the spring 125, with the pawl 119 in engagement with one of the teeth 107 to maintain the disk 82'

in the desired position, and so as to bring one of the respective teeth 117 or the flexing tooth 118 in engagement with one of the teeth 107 to permit of the movement of the disk 82' and consequently the platen 13 the desired number of spaces, the flexible connection or cord 122 is trained over the rollers 123 and 124 and has one end connected to the carriage 112 to move the same against the tension of the spring 125, this structure being clearly illustrated in Figs. 5 and 6. This flexible connection 122 is connected to the pivoted bail or lever 126, carried upon the shaft 127 within the casing, this bail or lever 126 being operably connected to the controlling members of the respective motors 128, there being five of these motors each of a different magnitude of movement, so as to control the relative movements of the lever 126 and consequently the difference of pull upon the cord 122 so as to present the selected one of the respective pawls 118, 117 or 116, to its respective tooth 107 of the dial 82' and thus consequently permit the necessary movement of the platen 13. By this means, it will be seen that the actuation of the selector 2, due to the movement of any one of the levers 42 will control the actuation of any one of the motors 128, or any number thereof, so as to properly actuate the lever 126 and the respective pawls 118, 117 and 116, so that the escapement drum 82' will be permitted to move the desired distance through its motor controls 62 and 63 heretofore described.

What is claimed is:

1. A typewriter, including a frame, a vertically reciprocatory carriage, a horizontally rotatable platen mounted therein, a motor actuated means for elevating the carriage, a plurality of selective motor actuated means for rotating the platen one or more spaces at a time, and motor actuated means for returning the carriage.

2. A typewriter, including a frame, a vertically reciprocatory carriage, a horizontally rotatable platen mounted therein, a plurality of selective motor actuated means for rotating the platen one or more spaces at a time, a motor actuated means for elevating the carriage, a motor actuated means for returning the carriage, and selective means for causing the individual actuation of any of the motors.

3. A typewriter, including a frame, a vertically reciprocatory carriage, a horizontally rotatable platen mounted therein, a motor actuated means for elevating the carriage, a plurality of selective motor actuated means for rotating the platen one or more spaces at the time, motor actuated means for returning the carriage, a plurality of type bars, a plurality of depressible keys for actuating the type bars, means operably connected with the keys for causing the actua-

tion of a selected platen rotating motor coincidently with the depression of a key, key actuated means for operating the motor actuated means for elevating the carriage, and 5 key actuated means for operating the motor actuated means to return the carriage.

4. A typewriter, including a frame, a rotatable platen, a vertically reciprocatory carriage carrying the platen, a plurality of motor actuated means for imparting varying latitudes of rotation to the platen, a plurality of type bars, keys for actuating the type bars, and a selective device for each motor actuated means, whereby the platen is rotated in proportion to the number of type bars operated simultaneously.

16 during line shifting.

5. A typewriter, including a frame, a ro-

tatable platen, a vertically reciprocatory carriage carrying the platen, a plurality of motor actuated means for imparting varying latitudes of rotation to the platen, a plurality of type bars, keys for actuating the type bars, and a selective device for each motor actuated means, whereby the platen is rotated in proportion to the number of type bars operated simultaneously.

20 In testimony that I claim the foregoing as my own, I have hereto affixed my signature in the presence of two witnesses.

JUAN G. HOLGUIN BURBOA.
